(57) **CLAIM**

We claim the ornamental design for a water view spigot, as shown and described.

DESCRIPTION

FIG. 1 is a front perspective view of a water view spigot showing the design thereof;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof;

FIG. 7 is a bottom view thereof;

FIG. 8 is a front perspective view of a closed water view spigot thereof; and,

FIG. 9 is a front perspective view of a water view spigot showing the water view spigot assembled to a water tank. In the drawings, the broken lines depict portions of the water view spigot that form no part of the claimed design.
